UNITED STATES PATENT OFFICE.

GEORGE H. WILLARD, OF HOPE DALE, MASSACHUSETTS, ASSIGNOR TO DRAPER CORPORATION, OF HOPE DALE, MASSACHUSETTS, A CORPORATION OF MAINE.

SELF-CONTAINED LATCHING MECHANISM FOR INTERMITTENT-THREAD-CUTTING TEMPLES.

Application filed November 5, 1926. Serial No. 146,391.

This invention relates to a thread cutting temple of the intermittently acting type such as employed in looms provided with automatic filling replenishing mechanism and in which the thread cutting mechanism is held in inoperative position by a detent latch element during the normal operation of the loom, but is rendered operative at the time of filling replenishment so as to sever the filling ends left at the selvage as the result of such replenishment.

One form of such an intermittent thread cutting temple is disclosed in the patent to Stimpson, No. 1,552,016, September 1, 1925.

Therein the prime actuating element for effecting the movement of the detent latch to render the cutting mechanism operative is the usual shuttle feeler which moves when filling replenishment is to take place and the movement of this shuttle feeler acting through certain controlling mechanism described in the said patent and located remote from the temple is transmitted through a Bowden wire to the detent latch. The present invention in the specific form illustrated is disclosed in connection with such a construction. But the invention in its broader aspects is not restricted to this particular type of mechanism because various means may be employed to effect the movement of the latching mechanism at the desired time as, for example, when filling replenishment takes place.

The object of the present invention is primarily to provide a self-contained latching mechanism which may readily be bodily attached or secured to a standard thread cutting temple. The invention thus renders it a comparatively simple matter to equip existing looms provided with thread cutting temples with the mechanism necessary to secure intermittent action of the thread cutting mechanism.

The object of the invention is further to provide means included in the self-contained latching mechanism by which the latching mechanism may be adjusted to insure accurate correlation with the cutting mechanism.

These and other objects and features of the invention will appear more fully from the accompanying description and drawings and will be particularly pointed out in the claims.

As the general construction and operation of various types of intermittent thread cutting temples for looms are well known and familiar to those skilled in the art, and as the patent to Stimpson above referred to discloses in full detail one form of such mechanism, and as the present invention is not concerned with the particular mechanism employed for effecting the movement of the latching mechanism, it will only be necessary here to illustrate and describe a simple and preferred form of construction embodying the invention when used in connection with the mechanism disclosed in the said Stimpson patent.

In the drawings:

Fig. 1 is a side elevation of an intermittent thread cutting temple with a preferred form of the present invention mounted thereon.

Fig. 2 is a view in perspective of the base element of the self-contained latching mechanism shown in Fig. 1.

Fig. 3 is a top plan view of the construction shown in Fig. 1.

Fig. 4 is a view in transverse cross section taken on the line 4-4 of Fig. 3.

The thread cutting temple illustrated is of a well known and familiar type. The temple stand is an elongated box-like structure comprising bottom and top members. The bottom member has a flat bed plate 1 and a vertical wall 2. The top member has a vertical wall 3 opposed to the wall 2, a top plate 4 extending above the bed plate 1, and a flange 5 resting on the bed plate 1 and secured thereto by screws 6. An elongated slot 7 formed in the flange 5 and bed plate 1 provides a passageway for the usual bolts by which the temple stand is secured to the breast beam of the loom. The temple head 8 is carried by or formed integrally with the temple shank 9 which is mounted to slide longitudinally in the stand. The temple head and shank are projected rearwardly by a usual spring 10 surrounding the shank in the stand and forwardly by engagement of the lay of the loom with the usual heel 11 depending from the temple head.

The cutting mechanism illustrated comprises a fixed cutter blade 12 mounted at the front of the temple head and a movable cutter blade 13 mounted to rock and reciprocate in the temple head and cooperate with the fixed blade. This movable cutter member is

provided with the usual depending heel 14 which, when struck by the lay, effects the cutting movement while the usual spring connected at its upper end to the shank 9 and at its lower end to a stud 16 projecting laterally from the heel 14 effects the movement of the movable cutter member to its forward projected position.

The present invention is not concerned 10 with any specific form of thread cutting temple and the construction just described is employed simply for illustration.

In the intermittent type of thread cutting temple the thread cutting mechanism is normally held inoperative and in the construction illustrated this is secured by providing the movable thread cutting member 13 with a laterally extending stud or projection 17 which is engaged by a detent latch when the 20 movable cutter member is in its inoperative or retracted position. The present invention has to do with the latching mechanism which, when in latching position, renders the cutting mechanism inoperative and, when in 25 unlatching position, renders the cutting mechanism operative. In the construction illustrated, the movement of the latching mechanism to the former position is effected by a spring 18 and to the latter position is 30 effected by an actuator transmitter in the form of a Bowden wire 19. But the invention broadly considered is independent of the particular instrumentalities for effecting these movements. In the construction illustrated, the Bowden wire 19 may be actuated, 35 by such a construction as disclosed in the Stimpson patent referred to, upon the call for filling replenishment.

The feature of the present invention is 40 that the entire latching mechanism is embodied in a self-contained structure which may be readily attached to a standard form of temple. Thus existing looms in use in mills and already having thread cutting temples may readily be equipped with mechanism whereby the desired intermittent operation of the temple is provided. All that it 45 is necessary to do is to attach this self-contained latching mechanism to the temple, and make the necessary connections to the actuating element. If the thread cutting mechanism is not provided with a suitable part to 50 cooperate with the latch, it may readily be supplied. If the thread cutting temple is of 55 the type illustrated and there is no stud on the movable thread cutting member, it is an easy matter to furnish with the self-contained latching mechanism a new movable thread cutting member having a stud or projection such as 17, which may readily be 60 slipped in place in lieu of the one in use.

This self-contained latching mechanism includes a base, a preferred form of which is 65 shown separately in Fig. 2. This base is shown as a plate 20 adapted to fit against

the temple and be secured thereto in some convenient position. As shown, the base corresponds in general shape to the vertical side wall 2 of the temple stand and is readily secured firmly in place thereto by bolts 70 or rivets 21 passing through holes 22 in the plate 20 and into holes drilled or tapped in the wall 2. This plate 20 of the base is provided with suitable mountings for the detent latch. In the construction illustrated, this 75 requires simply two studs 23 and 24 which are formed integrally or rigidly with the plate 20 and project laterally therefrom. Bearing shoulders 25 are preferably formed on the plate 20 at the base of the studs 23 80 and 24. The stud 24 forms the fulcrum for a detent latch 26 such as shown in the Stimpson patent referred to and which is adapted to cooperate with the stud or projection 17 or the movable cutter member. The stud 85 23 forms the fulcrum for a second lever 27 such as that shown in the Stimpson patent, which lever is provided with a stud 28 engaging the forked end of the detent latch 26. Cotter pins 29 or other suitable devices 90 secure the two levers on the studs 23 and 24. The spring 18 already referred to is seated at one end in a projection 30 extending laterally from the plate 20 and is seated at this other end in the end of the lever 27. This 95 spring thus mounted on the base acts to move the detent latch 26, and to maintain it in, the latching position, whereby the cutting mechanism is rendered inoperative.

An apertured boss 31 is formed integrally 100 with the base 20, with its aperture 32 located beneath the end of the lever 27. The Bowden wire 19 is mounted in the aperture of this boss 31 and locked in place by a set screw 33 passing radially through the boss. 105 Thus the boss presents a connection to receive the actuation transmitter, or in this case the Bowden wire, by means of which the detent latch is moved to its unlatching position to release and render the cutting 110 mechanism inoperative.

The present invention also provides in this self-contained structure means for adjusting the position of the effective end of the detent latch relatively to its mounting on the base. 115 This, in the specific form illustrated, consists in forming the detent latch lever in two parts, one provided with a bolt and nut 34 and the other with a slot 35, by means of which, after the base has been secured in 120 place on the temple, the effective end of the detent latch may be adjusted to any desired position with respect to the fulcrum 24 that may be found necessary to insure the accurate correlation of the detent latch with the 125 cooperating element, such as the stud 17, of the cutting mechanism.

Having thus described the invention, what is claimed as new, and desired to be secured by Letters Patent, is:

1. A self-contained latching mechanism for an intermittent thread cutting temple comprising a base, a two-part detent latch mounted on the base and movable thereon between latching position, which renders the cutting mechanism inoperative, and unlatching position, which renders the cutting mechanism operative, means mounted on the base acting to move the detent latch to one of said positions, a connection on the base to receive an actuation transmitter by means of which the detent latch is moved to the other of said positions, means for securing the base to the temple and means for adjustably securing together the two parts of the detent latch to adjust the effective end of the detent latch relatively to the mounting of the latch on the base in order to insure accurate correlation of the detent latch and cutting mechanism when the base is secured to the temple.

2. A self-contained latching mechanism for an intermittent thread cutting temple

comprising a base, a detent latch lever pivotally mounted on the base, having its detent arm in two parts adjustably secured together and movable on its pivot between latching position, which renders the cutting mechanism inoperative, and unlatching position, which renders the cutting mechanism operative, a spring mounted on the base acting to move the detent latch to latching position, a connection on the base to receive an actuation transmitter by means of which the detent latch is moved to unlatching position, and means for securing the base to the temple stand, the said adjustment of the two parts of the detent arm of the latch permitting the adjustment of the detent end relatively to the mounting of the latch on the base in order to insure accurate correlation of the detent latch and cutting mechanism when the base is secured to the temple.

In testimony whereof, I have signed my name to this specification.

GEORGE H. WILLARD.
